TELEPHONE SET.

1,099,550.

Specification of Letters Patent. Patented June 9, 1914.

Application filed September 3, 1913. Serial No. 737,945.

To all whom it may concern:

Be it known that we, PETER L. JENSEN, a subject of the King of Denmark, and EDWIN S. PRIDHAM, a citizen of the United States, both residing at Napa, in the county of Napa and State of California, have invented new and useful Improvements in Telephone Sets, of which the following is a specification.

10 This invention relates to telephones and particularly to the combination of telephone receiver and transmitter.

The object of the present invention is to provide a practical commercial telephone set adapted to be used when it is not convenient to hold the receiver to the ear.

The invention consists of the parts and the combination and construction of parts as hereinafter more fully described and 20 claimed, having reference to the accompanying drawing in which the figure is an elevation in partial section of a telephone set representing the invention.

In receiving telephone messages it is often 25 convenient to have one hand free and for this reason we employ tubes 2-3 to convey the sound from a stationary sound box 4 and connect one of the tubes, as 2, from the sound box to a hollow, fixedly supported 30 arm 5 which carries an ear piece 6 against which the head can be leaned. This arm 5 may be made adjustable in length by means of the clamp screw 7, so that the ear-piece 6 which is mounted upon it is 35 at a convenient place for the listener. This hollow arm 5 is supported through an adjustable joint 8 to the receiver box which permits a change of position; that is, it may be adjusted through a certain angle, 40 or may be pushed back out of the way when not in use. This hollow arm is made of metal, or other suitable firm material, and is strongly supported by the receiver box A; the joint 8 between the arm and the 45 box being so made that when the arm is placed in a certain position it remains solidly in place. The other side of the sound box 4 is connected by means of the flexible tube 3 to a hollow handle 9. One end of this hollow handle ends in an ear-piece 10 and on the other end there is mounted a transmitter 11 at a convenient distance from the ear-piece 10. The transmitter and re-

ceiver are electrically connected to the telephone circuit by means of a hook switch 12 upon which the hollow handle 9 containing the transmitter 11 and ear-piece 10 normally rests. The lifting of this handle puts the apparatus in working condition. When the handle 9 is lifted off its support, the action of a spring 13 causes the contacts 14 and 15 to be closed thus putting the receiver and transmitter into operative condition. The type of receiver shown in the figure comprehends the movement of a coil placed in a strong magnetic field, and is illustrated in our prior Patent #1,051,113, January 21, 1913. In the present case the coil 16 is shown attached to the diaphragm 17. The magnets are not shown for the sake of clearness. The connections from the transmitter and receiver coil to the contact pieces of the hook switch are not shown, but it is understood that these connections are made after the well known practice.

In practice the hollow handle on which is mounted the ear-piece and transmitter is lifted from the hook which puts the instrument into operative condition. When the ear-piece of this handle is placed to the ear 30 the transmitter is at the proper distance from the mouth for good articulation. The other ear may then be pressed against the ear-piece 6 of the supported hollow arm 5. In many cases it may be only necessary to 35 use the hollow handle for listening, but in case the speech is very weak we have found it to be a great advantage to listen with two tubes.

The novelty of our invention is in the use 90 with a telephone receiver containing a sound box, of a supported adjustable hollow arm, one end of which terminates in an ear-piece, the other end being connected by a tube to one side of the sound box, and a hollow handle connected by a flexible tube to the other side of the sound box, one end of which terminates in an ear-piece and the other end having mounted upon it a transmitter.

It should be understood that our invention 100 is not limited to the class of receivers shown in the figure, but it is adapted to be used with any receiver when for any reason it is not desirable to hold the receiver itself to the ear.

Having thus described our invention what

we claim and desire to secure by Letters Patent is—

1. In a telephone set, the combination with a sound box containing a diaphragm actuated by telephonic currents, of a movable hollow handle, said hollow handle having mounted upon it a transmitter, one end of said hollow handle terminating in an ear-piece, the other end of said handle being connected by a tube to said sound box.
2. In a telephone set, the combination with a telephone receiver provided with a sound box, said sound box being divided into two air chambers by the diaphragm of said receiver, of an adjustable supported hollow arm, one end of said arm terminating in an ear piece, the other end of said arm being connected by a tube to one of said air chambers, and a movable hollow handle, said handle having mounted upon it a transmitter, adapted to be included in the telephone circuit, one end of said hollow handle terminating in an ear-piece, the opposite end of said hollow handle being connected by a tube to the other of the afore-mentioned air chambers.
3. In a telephone set, comprising a transmitter, hook switch, and a receiver, said receiver having its diaphragm placed in a sound box, the position of said diaphragm forming two air chambers in said sound box, an adjustable supported hollow arm, one end of said arm terminating in an ear-piece, the other end of said hollow arm being connected by a tube to one of said air chambers,

and a movable hollow handle, upon said movable hollow handle is mounted the transmitter, one end of said hollow handle terminating in an ear piece, the other end of said handle being connected by a tube to the other of said air chambers, said hollow handle in rest position being supported by said hook switch, substantially as described.

4. In a telephone set, the combination of a hollow movable handle, said hollow handle having mounted upon it a transmitter, adapted to be included in the telephone circuit, one end of said hollow handle terminating in an ear-piece, the other end of said hollow handle adapted to be connected by a flexible tube to a sound box, and an adjustable supported hollow arm, one end of said hollow arm terminating in an ear piece, the other end of said hollow arm connected by a tube to said sound box, with a telephone receiver of which said sound box forms a part, said telephone receiver adapted to be included in the telephone circuit, and a hook switch operated by the weight of said hollow handle by the removal of which said transmitter and receiver are put into operative condition, as hereinbefore set forth.

In testimony whereof we have heretunto set our hands in the presence of two subscribing witnesses.

PETER L. JENSEN.
EDWIN S. PRIDHAM.
